UNITED STATES PATENT OFFICE.

BERTRAM J. GOLDSMITH AND EMIL KGBE, OF NEW YORK, N. Y., ASSIGNORS TO PERFECT WINDOW REGULATOR CORPORATION, OF LONG ISLAND CITY, NEW YORK, A CORPORATION OF DELAWARE.

WINDOW REGULATOR.

Application filed May 28, 1925. Serial No. 33,378.

This invention relates in general to improvements in the art of window controlling mechanism and is specifically designed for use in closed automobile construction.

It is one of the principal objects of the invention to provide an easily controlled mechanism to lock a freely sliding window in any adjusted position.

It is another object to provide a checking device cooperating with the movable window so as to prevent sudden movements thereof to closed position.

These and other objects will appear from the following description considered in connection with the drawings in which:

Fig. 1 represents an elevational view of a portion of an automobile door showing our invention applied thereto.

Fig. 2 is a horizontal section of the structure shown in Fig. 1.

Fig. 3 is an enlarged elevational view of a portion of the controlling mechanism.

Fig. 4 is a section thereof on the line 4-4 of Fig. 3.

Fig. 5 is a horizontal section on the line 5-5 of Fig. 3.

According to the construction herein disclosed the movable window indicated at 10 is slidably mounted upon a supporting frame shown as an automobile door 12 including the side members 14 having suitable window guides 15. The door 12 includes a window opening adjacent the upper portion thereof and a window well beneath the same such that the window can be moved upwardly into closed position or lowered into the window well so as to leave the window opening unobstructed.

The construction described above may be formed in any preferred manner the details thereof forming no part of our present invention.

This invention contemplates controlling the position of the window by having the same manually movable into lowered or opened position and automatically locking the same in that position. A suitable releasing means is provided to permit the window to move automatically to closed position, such movement of the window being broken or checked as will appear more fully below. The controlling mechanism for the

window includes a supporting plate 16 mounted upon the cross members 17 adjacent the inner face of the door although the plate may be supported by the adjacent side member 14 if desired. The plate 16 carries an operating arm 18 pivotally supported thereon as by means of the bolt 20, the outer or free end of the operating arm extending to and being operatively connected to the window 10. This is accomplished in the construction shown by mounting a roller 19 upon the free end of the arm, the roller moving in a channeled guide secured upon the lower portion of the window. The arm 18 is normally tensioned upwardly by means of the coiled spring 22 preferably coiled about the axis 20 for the arm 18. The spring 22 is supported by means of the plate 16 by having the end 23 thereof bent about an angular extension 24 of the plate. The inner end of the spring is passed between the sides of the forked shaft 20 for movement therewith. The spring 22 thus tensions the arm 18 upwardly and has sufficient strength to overcome the weight of the window 12 so that, unless otherwise obstructed, the spring moves the window 10 to its closed position. The arm 18 carries a series of ratchet teeth 25 mounted upon an arcuate plate 28 for a purpose to be referred to.

In order to hold the window in any adjusted position the latch member 26 carried by the plate 16 has a cam end 27 thereof arranged for engagement with the teeth 25 of the arm 18. The lever 26 is provided with an operating handle 30 projecting from the inner face of the door and operating in a slot 32 of the plate 16. The lever is held in latched position by any suitable means as for example by the spring 34 engaging the latching end thereof.

Since it is contemplated to lower the window by hand it is preferred to mount a hand grip 36 upon the upper edge thereof although obviously this is not essential, or it may be formed as an integral portion of the window if preferred.

It will be seen that as the window is moved downwardly the arm 18 will be moved about its pivot and that the series of teeth 25 will progressively pass the latching cam 27. If the window is released at any time the latch

will come into engagement with one of the teeth 25 and hold the window in this position until the latch is manually released.

In order that the window will not rise too rapidly subject to the influence of the spring 22, it is preferred that the checking device indicated generally at 36 be employed. It is preferred that the checking device be carried by the supporting plate 16 so that the whole window controlling mechanism may be mounted as a unit. To this end the plate carries a pivoted yoke 38, pivoted to the plate as at 39, to which there is welded or otherwise rigidly secured the tubular shaft 40. A piston in the form of a rod 42 is slidably mounted within the tubular member 40 and extends to and is pivotally connected to the operating arm 18 adjacent the free end thereof as indicated at 43. The outer surface of the rod 42 fits within the tubular member 40 with a certain degree of looseness so that there will be some leakage of air around the rod 42 when the rod slides in the tube 40. The closed end of the member 40 is provided with an opening 44 normally closed by means of a ball valve including the ball 46 and spring 48. The spring operates between the ball and the stop 50 carried by the member 40 so as to hold the valve normally closed.

The operation of this device is as follows: When it is desired to lower the window it is lowered by means of the hand grip 36. This operation is not difficult since a lowering movement of the window draws the rod 42 out of the cylindrical member 36, the ball 46 being displaced to permit the entrance of air through the opening 44. During this movement the latch 26 slides progressively over the teeth 25 until the window is released. The latch then engages an adjacent tooth of the arcuate rack 28 and the window is held in this position until manually released by means of the handle 32. When the latch 26 is manually moved to unlatched position and the window is accordingly freed it will move upwardly under the influence of the spring 22. Since the window will be subject to the influence of the dashpot 36 its upward movement will be considerably restrained as the ball 46 will have closed the opening 44. The result is that the window may be stopped by the latch 26 or by reaching the upward limit of its movement without tending to jar or break the window or any of the operating parts thereof.

While we have shown and described certain specific constructions it is to be understood that these are merely illustrative and that the invention is limited only as set forth in the appended claims.

We claim as our invention:

1. In combination with a supporting structure, a slidable window carried thereby, counterbalancing means tending to maintain

said window in raised position, releasable stop mechanism for preventing said window from being raised, and means for limiting the speed of the upwardly moving window when said stop mechanism is released. 76

2. In combination with a supporting structure, a slidable window carried thereby, counterbalancing means tending to maintain said window in raised position, releasable stop mechanism for maintaining said window in various adjusted positions, means for releasing said stop mechanism, and means for limiting the speed of movement of said window in one direction, said last mentioned means being rendered inoperative 75 during the movement of said window in the opposite direction. 30

3. In a window controlling mechanism, a movable operating member operatively associated with said window, means tensioning 85 said member for movement in one direction, manually controlled stop mechanism for maintaining said window in various adjusted positions and a dashpot operatively connected to said mechanism to check movements of the same when moved by said tensioning means. 90

4. In a window controlling mechanism, a movable operating member operatively associated with said window, means tensioning 95 said member for movement in one direction, manually controlled stop mechanism for preventing said means from functioning, and a dashpot operatively connected to said mechanism to check the same when moved 100 by said tensioning means, said dashpot being rendered inoperative when said operating member is moved against the force of said tensioning means.

5. In a window regulator, a pivoted operating arm operatively connected to said window, spring means tending to rotate said operating arm in one direction, stop mechanism to retain said arm in various adjusted positions, manual means for controlling said 105 stop mechanism, and a speed checking device for maintaining substantially constant speed of movement of said operating arm when released from said stop mechanism. 110

6. In a window regulator, a rotatable 115 operating member operatively connected to said window, spring means tending to rotate said operating member in one direction, stop mechanism to retain said member in any adjusted position, manual means for 120 controlling said stop mechanism and a fluid containing checking device operatively associated with said mechanism for preventing unrestricted movement of said member.

7. In a window controlling mechanism, a 125 pivoted operating member operatively connected to said window, spring means for rotating said member in one direction, a checking device for preventing unrestricted movement of said member under the in- 130

- fluence of said spring means, said checking device including a cooperating cylinder and piston operatively associated with said mechanism.
8. In a vehicle window controlling mechanism, a slideable window, means for moving said window, and speed responsive checking devices operatively associated with said window for preventing unrestricted movement of said window in one direction.
9. In combination with a supporting plate, an operating arm pivoted thereon, spring means supported by said plate for rotating said arm in one direction, a manually controlled stop mechanism carried by said plate, a movable member connected for rotation with said arm and adapted to be engaged by said stop mechanism, and an automatic speed checking device carried by said plate and operatively associated with said mechanism for checking the speed of movement of said arm in one direction.
10. In combination with a supporting plate, an operating arm pivoted thereon, spring means supported by said plate for rotating said arm in one direction, a manually controlled stop mechanism carried by said plate, a movable member connected for rotation with said arm and adapted to be en-
- gaged by said stop mechanism, and a speed checking device carried by said plate and operatively associated with said mechanism for preventing unrestricted movement of said arm in one direction, said speed checking device including a co-acting piston and cylinder engaging between a point on said arm remote from the pivot thereof and said plate.
11. In combination with a supporting frame provided with window guides, a slideable window carried thereby, controlling mechanism for said window including a pivoted arm supported by said frame and operatively connected to said window, spring means tensioning said mechanism in a direction to move said window to closed position and of sufficient strength to move the same unless otherwise checked, manually controlled stop mechanism to prevent upward movement of said window, and speed limiting mechanism for preventing unrestricted movement of said window when released from said stop mechanism.

Signed at New York, in the county of New York and State of New York this 27th day of May A. D. 1925.
